(57) CLAIM

The ornamental design for a banjo pot sub-assembly, as shown and described.

DESCRIPTION

FIG. 1 shows a top view of a banjo pot sub-assembly including a banjo pot shell residing within a banjo pot flange shown in phantom.

FIG. 2 shows a bottom of view of the banjo pot sub-assembly including the banjo pot shell residing within the banjo pot flange shown in phantom.

FIG. 3 shows a side view of the banjo pot sub-assembly including the banjo pot shell residing within the banjo pot flange shown in phantom.

FIG. 4 shows an isometric view of the banjo pot sub-assembly including the banjo pot shell residing within the banjo pot flange shown in phantom.

FIG. 5 shows a top view of a banjo pot sub-assembly including a banjo pot shell.

FIG. 6 shows a bottom of view of the banjo pot sub-assembly including the banjo pot shell.

FIG. 7 shows a side view of the banjo pot sub-assembly including the banjo pot shell.

FIG. 8 shows an isometric view of the banjo pot sub-assembly including the banjo pot shell; and,

FIG. 9 shows a cross-sectional side view of the banjo pot sub-assembly including the banjo pot shell residing within the banjo pot flange shown in phantom.

The banjo pot flange is shown in FIGS. 1-4 and 9 in phantom lines for illustrative purposes only and forms no part of the claimed design.
